US00D927052S

(12) **United States Design Patent** (10) **Patent No.:** **US D927,052 S**
(45) **Date of Patent:** **** Aug. 3, 2021**

(54) **CARTRIDGE**

(71) Applicant: **JOYETECH EUROPE HOLDING GMBH**, Zug (CH)

(72) Inventors: **Weihua Qiu**, Changzhou (CN); **Jialian Zhao**, Changzhou (CN)

(73) Assignee: **JOYETECH EUROPE HOLDING GMBH**, Zug (CH)

(**) Term: **15 Years**

(21) Appl. No.: **29/706,634**

(22) Filed: **Sep. 21, 2019**

(30) **Foreign Application Priority Data**

Mar. 21, 2019 (CN) 201930119461.4

(57) **CLAIM**

The ornamental design for a cartridge, as shown and described.

DESCRIPTION

FIG. 1 is a top, right front perspective view of a cartridge showing our new design;

FIG. 2 is a bottom, left back perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

The broken lines shown in the drawings depict portions of the cartridge that form no part of the claimed design.

1 Claim, 6 Drawing Sheets
